UNITED STATES PATENT OFFICE

125,501

DESIGN FOR A BED UNIT

Maud Christine Thompson, San Jose, Calif.

Application February 5, 1940, Serial No. 90,043

Term of patent 3½ years

To all whom it may concern:

Be it known that I, Maud Christine Thompson, a citizen of the United States, residing at San Jose, county of Santa Clara and State of California, have invented a new, original, and ornamental Design for a Bed Unit, of which the following is a specification, reference being had to the accompanying drawing, forming a part thereof.

looking at the front side and one end, and showing my new design.

Figure 2 is a similar view of the bed unit, looking at the rear and the opposite end.

I claim:

The ornamental design for a bed unit, as shown.
